UNITED STATES PATENT OFFICE

JACOB A. SCHOEDINGER, SR., OF MIAMI, FLORIDA

DESIGN FOR AN AUTOMOBILE TIRE

Application filed January 2, 1932. Serial No. 42,345. Term of patent 14 years.

To all whom it may concern:

Be it known that I, JACOB A. SCHOEDINGER, Sr., a citizen of the United States, residing at 325 N. W. 45th Street, in the city of Miami, county of Dade, State of Florida, have invented a new, original, and ornamental Design for Automobile Tires, of which the following is a specification, reference being had to the accompanying drawings, forming part thereof.

Fig. 1 is a plan view of a section of an automobile tire showing my new design.

Fig. 2 is a side elevation of the same, and Fig. 3 is a transverse section on the line 3—3 of Fig. 1.

I claim:

The ornamental design for an automobile tire as shown.
